UNITED STATES PATENT OFFICE.

GERARD DE MONTRICHARD, OF MONTMÉDY, FRANCE.

PUMP.

SPECIFICATION forming part of Letters Patent No. 432,426, dated July 15, 1890.

Application filed July 23, 1888. Serial No. 280,751. (No model.) Patented in France April 15, 1887, No. 182,754, and November 22, 1887, No. 187,061; in Belgium May 14, 1887, No. 77,454, September 16, 1887, No. 78,900, and November 3, 1887, No. 79,394; in England August 29, 1887, No. 11,700; in Germany September 22, 1887, No. 43,403, and in Italy September 26, 1887, No. 135/22,359.

To all whom it may concern:

Be it known that I, GERARD DE MONTRICHARD, a citizen of the Republic of France, residing at Montmédy, France, have invented 5 certain new and useful Improvements in Pumps, also applicable as Motor-Engines, (for which I have obtained Letters Patent in France April 15, 1887, No. 182,754, and November 22, 1887, No. 187,061; in Great Britain August 29, 1887, No. 11,700; in Belgium September 16, 1887, No. 78,900, May 14, 1887, No. 77,454, and November 3, 1887, No. 79,394; in Germany September 22, 1887, No. 43,403, and in Italy September 26, 1887, No. 135/22,359,) of which the following is a full, clear, and exact specification.

According to this invention the piston of a pump-barrel has imparted to it a rotary motion combined with the to-and-fro motion. 20 The rotary motion may be transmitted to the piston-rod either by a crank, by a pulley and belt, by other gearing, or by other suitable known means. The to-and-fro motion is imparted by means of rollers acting upon obliquely-curved surfaces, which either cause 25 the piston to slide upon its rod, or, if it be fixed thereon, the piston-rod to slide through the stuffing-box.

Pumps constructed as above described may 30 be used for pumping liquids and gases of all kinds. In this apparatus used as a pump the said rollers are placed in the interior of the cylinder, and the oblique surfaces are formed on the ends of the piston, the openings for suction and discharge being formed 35 through the side of the cylinder in suitable position.

In the accompanying drawings are shown 40 various arrangements for carrying out the above-described invention.

Figure 1 shows a longitudinal section of an arrangement in which the piston is fixed 45 on the piston-rod, the obliquely-curved surfaces being formed on the piston and acted upon by rollers within the cylinder. Fig. 2 shows a longitudinal section of an arrangement in which the piston slides upon the piston-rod. Fig. 3 shows a part end elevation and cross-section of the arrangement

shown in Fig. 1. Figs. 4 and 5 show sections 50 of the boss of the piston. Fig. 6 shows a longitudinal section of an arrangement having a piston of different form. Fig. 7 shows a cross-section of the same.

With these machines the cylinder is generally arranged horizontally, the piston-rod passing through stuffing-boxes in which it works either only with a rotary motion or with a combined rotary and longitudinal motion, according as the piston is loose upon the rod or fixed thereon. In the construction shown at Figs. 1, 2, and 3 the piston F consists of a hollow cylindrical body divided internally into two spaces by an oblique partition W, and having its ends formed with 55 beveled or oblique curved or cam surfaces I, while the cylindrical shell is formed with openings, the positions of which are determined by those of the admission and discharge ports of the cylinder. This piston is, 60 according to the arrangement at Fig. 1, fixed on the rod A by means of a key or other suitable device, and is adjusted in position in the cylinder E so that the surfaces I are in contact with the rollers J, which are 65 free to turn on threaded pins screwed in the side of the cylinder E. The surfaces or cam-faces I being oblique or beveled, it is of course desirable that the rollers J, forming 70 inwardly-projecting studs for holding the piston in place, should also be beveled—that is, should be conical—so that they will fit evenly against such faces I, and thus as the faces wear away and the piston begins to play between the rollers it is only necessary to give 75 the threaded pins a turn, whereby such rollers will be forced down into close contact with the beveled faces of the cams I and hold the piston snugly in place. The cylinder has at its center two diametrically-opposite branched 80 openings G and H, constituting, respectively, the inlet and discharge ports. The piston-rod A passes through two stuffing-boxes B and C on the covers of the cylinder. It will be seen that if the piston rod or shaft A is rotated by the fast and loose pulleys mounted thereon, as shown, the piston F in rotating 85 causes the oblique surfaces I to slide against

the rollers J, and is thereby made to move backward and forward in the cylinder, in which motion the piston-rod participates. In revolving the piston is made alternately to bring its side openings opposite the inlet and discharge ports, and at such times the to-and-fro motion of the piston produces in the one case a suction action, drawing liquid from the inlet-port into the cylinder, and in the latter case an expelling action, forcing the liquid previously drawn into the cylinder out through the discharge-pipe.

In some cases it is preferable to use the arrangement shown at Fig. 2, in which the piston rod or shaft A does not partake of the to-and-fro motion of the piston, which slides to and fro with a square hole upon a square part D of the shaft, as shown at Fig. 4. In this case the one end of the shaft A does not require to pass through a stuffing-box on the cylinder-cover, but runs with its cylindrical end in a cylindrical cup-bearing C, formed on the inner side of the cover. The piston rod or shaft A may in the case also be formed cylindrical at D, having a feather M fixed thereon, as at Fig. 5, over which the piston slides, with a corresponding groove. The arrangement and action of the machine are otherwise just the same as previously described.

The construction shown at Figs. 6 and 7 differs from that above described in the form of the piston, which in this case consists of a simple disk obliquely formed, in the cylindrical periphery of which fits the surface of the cylinder, while curved paths I, formed on its two faces, slide in contact with the rollers J, revolving, as before, upon studs G in the side of the cylinder, the piston in being rotated thus caused by the rollers to slide to and fro in the cylinder, either loose upon the piston-rod or fixed thereon, so that the piston-rod slides with it. Thus if in the drawings at Fig. 6 the piston is made to slide from right to left in rotating, the cylinder being filled with liquid, it will force out the body of liquid contained in the left-hand end of the cylinder, while it will at the same time draw in a corresponding charge at the right-hand end. With this arrangement the inlet and discharge ports A B, Fig. 7, instead of being placed at the ends of the cylinder, can be placed at the middle in line with each other, opening on each side of the piston immediately beyond the point where it is always maintained in the same longitudinal position relatively to the cylinder by the rollers J. The rotary motion of the piston taking place at a uniform speed, the speed of the to-and-fro motion will be variable, being practically zero at each end position, from which the motion is gradually accelerated toward the middle position and then gradually retarded toward the other end position. The flow of liquid

follows this movement; but if the passages 65 are sufficiently large it will continue in motion while the piston is passing the dead-points. Under these circumstances it is of advantage to employ a small air-cushion for compensating the variation in the speed. 70 The air-vessels may be arranged as at R R, Fig. 7, for this purpose, and they may be continuously fed with a small quantity of air by forming in the suction-pipe a small capillary opening admitting a few bubbles of air at 75 each stroke. This air-inlet may be produced either by loosening slightly one of the joints or by forming a small passage in one of the screw-plugs V at the top of the air-vessels R. The lubrication of the piston and rollers is 80 effected by a lubricator g, fixed on the cylinder.

Having now particularly described and ascertained the nature of this invention and in what manner the same is to be performed, I 85 declare that what I claim is—

1. The combination, with the cylinder having the inlet and exhaust ports and a piston-rod projecting into said cylinder, of an inclined piston located in said cylinder on said rod and having at each end a continuous inclined cam-surface, and two adjustable conical rollers located in said cylinder and bearing against both ends of said piston, substantially as set forth. 95

2. The combination, with the cylinder having the inlet and exhaust ports, of a piston in said cylinder consisting of a hollow body having the beveled cam-faces I formed on its extreme ends, and openings arranged between 100 said cam-faces to communicate alternately with the inlet and exhaust ports, said body being divided by a partition extending diagonally from end to end thereof, and said partition having a central square aperture, a piston-rod having a square portion fitting snugly in said aperture and whose length is equal to the range of motion of said partition, and adjustable beveled studs, between which said piston is arranged, adapted to bear against said 105 beveled cams I, substantially as set forth.

3. The combination, with the cylinder having inlet and exhaust ports and a piston-rod in said cylinder, of a piston on said rod having the cam-faces I I at both ends thereof, 115 and being provided with side openings between said cams adapted to communicate alternately with the inlet and exhaust ports, friction-rollers bearing at both ends of said piston against said cam-faces, and threaded 120 pins screwing into the cylinder and carrying said rollers for adjusting the latter relatively to said cam-faces I I, substantially as and for the purposes set forth.

GERARD DE MONTRICHARD.
